CLAIM

The ornamental design for a string light support, as shown and described.

DESCRIPTION

FIG. 1 is a perspective view of a string light support.

FIG. 2 is a front elevation view of the string light support, wherein the rear view is a mirror image thereof;

FIG. 3 is a side elevation view, wherein the other side view is a mirror image thereof.

FIG. 4 is a top plan view of the string light support.

FIG. 5 is a bottom plan view of the string light support; and, FIG. 6 is a bottom sectional view of the exterior of the string light support, viewed from the plane indicated on FIG. 2.

The broken lines immediately adjacent the shaded areas in FIGS. 1, 3, and 6, represent the bounds of the claimed design. All broken lines, showing portions of electrical wires and an exemplary electrical socket and light bulb, are for the purpose of illustrating the environment and are for illustrative purposes only. Surface shading is included for the purpose of showing contour of surfaces of the three-dimensional object and not for purpose of indicating color, texture, or reflectivity. The broken lines and surface shading form no part of the claimed design.
